(57) CLAIM

The ornamental design for a leg lace strips for pants, as shown and described.

DESCRIPTION

FIG. 1 is a perspective view of a leg lace strips for pants in an open configuration;

FIG. 2 is the perspective view of FIG. 1 where the leg lace strips is in a closed configuration;

FIG. 3 is a front view of the leg lace strips of FIG. 2;

FIG. 4 is a back view of the leg lace strips of FIG. 2;

FIG. 5 is a right side view of the leg lace strips of FIG. 2;

FIG. 6 is a left view of the leg lace strips of FIG. 2;

FIG. 7 is a top view of the leg lace strips of FIG. 2; and,

FIG. 8 is a bottom view of the leg lace strips of FIG. 2.

The broken lines on the surface of the leg lace strips represent stitching. The remaining broken lines showing portions of pants and shoes represent the portions of the design, which form no part of the claim.
